UNITED STATES PATENT OFFICE.

PAUL P. HEIN, OF NEW YORK, N. Y.

EXTENSION-BASE LAMP-BULB.

1,839,833.

Specification of Letters Patent.

Patented May 4, 1920.

Application filed November 5, 1918. Serial No. 261,247.

To all whom it may concern:

Be it known that I, PAUL P. HEIN, a citizen of the United States, and a resident of the city of New York, borough of Manhattan, in the county and State of New York, have invented a new and Improved Extension-Base Lamp-Bulb, of which the following is a full, clear, and exact description.

This invention relates to electric lamp 10 bulbs, and has particular reference to such lamps that are intended for use in connection with parabolic or other similar reflectors and in connection with which it is essential or important that the lamp bulbs 15 must be properly focused.

Among the objects of the invention, therefore, is to provide an electric lamp bulb having an adjustable or extensible base whereby when the base is locked in the reflector 20 socket the filament or bulb portion proper of the lamp may be adjusted axially toward or from the socket anchorage for focusing purposes.

A further object of the invention is to 25 provide an electric lamp bulb adapted to be fitted or adjusted for use in connection with any ordinary reflector, the socket of which has a fixed position with respect to the reflector.

With the foregoing and other objects in view the invention consists in the arrangement and combination of parts hereinafter described and claimed, and while the invention is not restricted to the exact details 35 of construction disclosed or suggested herein, still for the purpose of illustrating a practical embodiment thereof reference is had to the accompanying drawings, in which like reference characters designate 40 the same parts in the several views, and in which—

Figure 1 is a side elevation of one form of my improvement, parts being in longitudinal section.

Fig. 2 is a plan view of the same; and

Fig. 3 is a view substantially the same as Fig. 1, but indicating a slightly modified form of construction.

Referring now more specifically to the 50 drawings, I show a lamp bulb having a base comprising two relatively movable or extensible inner and outer base members 10 and 11, the one shown as being telescopic in the other and having means for holding 55 the two base parts in any desired relative position of adjustment along the axis afore-

said. The lamp filament 12 is supported as usual within the globe or bulb 13 and is carried by the inner base member 10, one of the leading-in wires being grounded in the inner base member 10 at any convenient point as at 14, while the other leading-in wire is connected to or constitutes a continuation of a convoluted member or spring 15 leading through the plug 16 in the anchorage 60 end of the outer base member 11 and fastened to a metallic tip or button 17.

The plug 16 is of porcelain or some other suitable insulating material and is fitted into the anchorage end of the sleeve member 11 where it may be locked as by means of the pins 18 which provide the lugs for locking the lamp base in the socket or reflector, not shown.

The sleeve member 11 is shown as being 75 slotted longitudinally at 19 with two parallel slits whereby there is formed a tongue 20 the outer free end of which is bent inward forming a sort of hook or catch 21 co-operating with a longitudinally serrated 80 portion 22 of the inner telescopic base member 10. The teeth formed at 22 have sloping inner and outer sides over which the catch portion 21 of the tongue 20 is adapted to slip when the bulb and its attached base 85 portion 10 are pushed inward or outward, but the catch serves to hold the bulb steady and reliably in any position in which it may be set or adjusted. The outer member 90 11 has sufficient frictional grip on the substantially cylindrical surface of the inner member 10 in all positions of adjustment of the lamp bulb, but permitting the longitudinal adjustment thereof in order to bring the filament 12 or source of light into proper 95 focus. This adjustment of the lamp bulb is provided for in the spring or convoluted member 15 arranged as indicated.

The construction in Fig. 3 so far as this present invention is concerned is essentially 100 the same as that above described with reference to the telescopic inner and outer members 10 and 11, but the leading-in wires of the filament 12' are connected to two metallic buttons 17', both of the leading-in 105 wires passing through or connected to convoluted members 15', both of which pass through the plug 16'. The inner and outer base members 10 and 11 for convenience of manufacture and adaptability to standard 110 reflector sockets are preferably cylindrical in form, and in this connection it will be

noted that the catch tongue 20 constituting a fixed part of the hollow cylindrical member or sleeve 11 and projecting into the notched or toothed portion 22 of the inner base member 10 constitutes not only a means to limit the longitudinal adjustment of the base member, but also serves to positively prevent relative rotation between the base members around the longitudinal axis of 10 the lamp.

I claim:

1. In an electric lamp, a base comprising an inner member, a sleeve surrounding said member and movable longitudinally relative thereto, a plug of insulation fitted in the socket end of the sleeve and spaced from the inner member aforesaid, said spacing being variable as a result of the relative movement aforesaid, a convoluted conductor in 15 the space between the plug and the inner member and having one end projecting through the plug, a lamp filament having one leading-in wire connected to said convoluted member, and the other leading-in 20 wire passing through the inner member first mentioned.
2. In an electric lamp bulb, the combination of inner and outer telescopic base members, means to lock the outer member in 25 fixed position leaving the inner member free to be moved inward or outward with respect thereto, one of said base members

having a flexible catch member coöperating automatically with the other member to hold the parts at any desired position longitudinally of the axis of the lamp, a bulb fixed to said inner base member, a filament within the bulb having leading-in wires passing through the inner base member, and a convoluted conductor to which one of the 40 leading-in wires is connected between the two relatively movable base members.

3. In an electric lamp, the combination of a base comprising a sleeve having longitudinal slits forming a flexible tongue, a 45 member fitted telescopically within the sleeve and having a series of depressions with which the free end portion of the tongue is adapted to coöperate, and a lamp bulb carried by said member having the 50 depressions.

4. In an extension base for lamp bulbs, the combination of a hollow cylindrical base member, an inner cylindrical member telescopically fitted in the hollow member, a 55 bulb fixed to the inner member, and flexible catch means acting between the inner and outer cylindrical members serving to hold the inner member at any desired longitudinal adjustment and also serving to prevent 60 rotation of the inner member in the hollow member.

PAUL P. HEIN.
